CLAIM

The ornamental design for an exercise rocking chair, as shown and described.

DESCRIPTION

FIG. 1 is a front-left quarter isometric view of an exercise rocking chair showing our new design;

FIG. 2 is a rear-left quarter isometric view thereof;

FIG. 3 is a left side elevation view thereof, a right side elevation view being a mirror image thereof;

FIG. 4 is a left side elevation view thereof showing an alternative position with the arm handles down;

FIG. 5 is a front elevation view thereof;

FIG. 6 is a rear elevation view thereof; and,

FIG. 7 is a left side isometric view thereof showing an alternative position with the arm handles down.

1 Claim, 7 Drawing Sheets
